SKATE SHARPENER

Gustav Russell Johnson, East Providence, R. I.

Application December 8, 1941, Serial No. 422,120

5 Claims. (Cl. 76—83)

This invention relates to hand manipulated skate sharpeners which may be carried in the pocket.

Objects of the invention include the provision of a portable hand manipulated skate sharpener which is small enough to be carried in the pocket and which is simple in construction and inexpensive to manufacture while being easy to operate and efficient in its intended function.

Further objects of the invention include the provision of a two-part frame which is attached to a wooden handle in such a manner as to present a cutter mounted in the frame, said cutter being cylindrical and rotatable for the presentation of various working surfaces; the provision of an easily grasped wooden handle having a two-part frame attached thereto in a recess thereof, one of the parts of the frame providing a bearing member for reception of the above mentioned cylindrical cutter and the other part providing a skate runner guide for approach of the skate to the cutter and at the same time providing means to firmly secure the first named frame part to the wooden handle.

Other objects and advantages of the invention will appear hereinafter.

Reference is to be had to the accompanying drawing in which

Fig. 1 is a plan view of a device embodying a skate sharpener according to my invention;

Fig. 2 is a side view of the skate sharpener;

Fig. 3 is a view similar to Fig. 2 but showing certain of the parts in section;

Fig. 4 is a section on line 4—4 of Fig. 3;

Fig. 5 is a view partly in section showing how the frame is assembled with respect to the handle;

Fig. 6 is a plan view of the cutter-bearing member; and

Fig. 7 is a view in side elevation of the cutter.

Referring to the drawing in detail there is shown a boat-shaped rectangular handle member 10 having opposite side edges thereof grooved as at 12 to provide a finger grip. The top surface of the handle is longitudinally recessed as at 14 to provide for recessed reception of the cutter frame, so that the latter will be firmly held to the handle but will not extend too far above the same, and the cutter will be positioned conveniently for the sharpening action.

The cutter is shown in detail in Figs. 3 and 7 and comprises a cylindrical cutter element 16 which may be made of tool steel or another appropriate material. The cutter is circumferentially milled to present a series of sharp circular

peripheral cutting edges 18, and the cutter is also formed with a pair of axially aligned end bearing elements 20 by which it is adapted to be mounted for rotary movement about its axis to present a plurality of cutting surfaces to the skate whereby the cutting edges 18 will not be worn away along a single side of the cutter. The cutting edges are triangular in cross-section and all face the same direction.

A plate 22, which may be originally stamped out in flat form, is provided with a pair of parallel spaced transverse slots 24 having a purpose to be described. The ends 25 of plate 22 are bent into right angled relationship with the plate on the same side thereof as is best seen in Fig. 3. The end pieces 25 are provided with apertures 28 which are in the form of a partial circle but which open into the ends of the end pieces with the center of the circles located within said end pieces, so that the members 20 of the cutter 16 may be inserted axially into apertures 28, but may not be removed therefrom by transverse forces acting on the cutter once it is seated in the end pieces 25 of the plate. Plate 22 is of a width to just be received in groove 14 as shown in Figs. 1, 4, and 5 and therefore any possible lateral play of plate 22 is obviated.

A second plate 30, which may also be stamped out in flat form originally, is formed with a central longitudinal slot 32 which acts as a skate runner guide when the device is used as a skate sharpener, slot 32 running lengthwise of the cutter 16 on handle 10, see Fig. 1. Slot 32 is positioned to occupy the central position of plate 30, and at each end of the slot it is enlarged by means of ring-like elements 34 to form round openings 36 which are larger in diameter than the cutter. Plate 30 terminates in end elements 38 formed as solid narrow continuations of ring-like members 34.

Plate 30 is bent at two points slightly spaced inwardly from the ends of slot 32 so that it presents a U-shaped member wherein slot 32 extends across the closed end of the U and slightly into the legs thereof which are formed by members 34 and 38. Leg members 38 extend through slots 24 in plate 22 traversing the handle from the bottom of groove 14 to the bottom of the handle, at which point they are bent inwardly towards each other to form locking fingers 40 which may be recessed into the handle as shown in Fig. 3 to completely lock all the parts together.

In assembling the device, plate 30 is bent to its U-shape except that fingers 40 are not bent inwards but still remain aligned with legs 38.

Openings 36 being considerably larger in diameter than the cutter, the latter is placed through the openings in the position shown in Fig. 3. Plate 22 is then bent into U-shape as shown in Fig. 3, and end pieces 26 may be sufficiently resilient to close over the end bearing pieces 20 of the cutter to hold the same in locked position against movement in every direction except that of rotation. Legs 38 of plate 30 will have been thrust through slots 24 in plate 22 in order to bring end pieces 26 of plate 22 into alignment with the cutter so as to position the end pieces 20 of the latter within the openings 28. The device is now assembled except for the attachment to handle 10 and this is done by setting the sharpener into groove 14 as shown in Fig. 3 and causing the legs 38 of plate 30 to penetrate the handle to the position shown in Fig. 5, whereupon fingers 40 are bent over and may be recessed in the handle to lock the two-part frame and the cutter thereto. Plate 22 may also be recessed into the bottom of groove 14 to additionally guard against endwise movement of the sharpener.

It will be seen from Fig. 5 that plate 22 is prevented from lateral movement in groove 14 and is held to the handle by reason of the ring-like portions 34 which securely hold the plate to the handle. Portions 34 will be seen to engage the corner formed by groove 14 so as to bear thereagainst and to additionally rigidify the device.

The skate blade S may be inserted in slot 32 to be guided thereby while handle 10 is manually grasped and reciprocated along the blade so that cutter edges 18 will sharpen the skate by actually removing material from its edge in one direction of movement, and the cylindrical shape of the cutter will provide for a skating edge similar to the hollow ground edge commonly desired.

It is contemplated that an abrasive stone could be used in place of cutter 16 but this type of stone ordinarily will be found to become grooved after service so as to lose the desired hollow ground profile of the skate runner.

Having thus described my invention and the advantages thereof, I do not wish to be limited to the details herein disclosed, otherwise than as set forth in the claims, but what I claim is:

1. In a device of the class described, a handle, a generally cylindrical sharpening element, a U-shaped frame member, bearings in the legs of said member for rotatably mounting said element, a second U-shaped frame member extending oppositely to the first named member and embodying a blade guide, the legs of said second member extending through a portion of

the first named member and penetrating the handle to hold both frame members and the cutter thereto.

2. A sharpener of the class described comprising a handle, a U-shaped frame member adapted to be secured to a surface of said handle with the legs of the frame member extending outwardly of said surface, openings in said legs, a cutter mounted in said openings, a second U-shaped frame member having its legs extending through a portion of said first named member and into the handle, said members being positioned so that their legs extend oppositely, enlarged portions on said second member abutting said first named member to act as fastening means to secure the frames to the handle, and a blade guiding slot in said second member.

3. A blade sharpener comprising a cylindrical sharpening element, a U-shaped frame member having bearings in its legs to rotatably support said element, the latter having a part of its periphery extending outwardly beyond the ends of the legs, a second U-shaped frame member having a blade guiding slot in its closed end, 25 a handle, means securing said first named member with its closed end flat against the handle, said means comprising legs on the second member and enlarged portions on said legs, said members having their legs extending oppositely to each other, and the slotted closed end of the second member being located at the side of the sharpening element opposite the handle.

4. A skate runner sharpener comprising an elongated handle, a U-shaped frame member having its closed end located flatly on said handle with its legs extending away from the handle, and substantially circular apertures in said legs, a second U-shaped frame member having its closed end spaced from said handle and legs 35 extending through the closed end of the first named frame member and penetrating the handle, a slot in said closed end of the second member, and a sharpening tool journaled in said apertures and located between and parallel to the closed ends of both frame members.

5. A blade sharpener comprising an elongated handle, a groove in a surface of said handle extending longitudinally thereof, a plate in said groove, upturned apertured ends on said plate forming bearings, a freely rotatable sharpening tool mounted in said bearings, and means securing said plate to said handle and including a blade guide, said means including a member surrounding said tool to form a head to hold the plate to the handle.

GUSTAV RUSSELL JOHNSON.
